John Deakins. Peterburgh. Febr

Setters Ball

April 2, 1835

The Schedule, referred to in the Letter Patent and, heretofore, part of the same, contains a description of the parts of the said Cutters, and of their improvement as a New Cutter.

To all to whom these presents shall come, Be it known that: I, the
Subscript of the Town of Petersburg in the County of Dinwiddie and State of Virginia
doe distribute & give out design improvement in the town of Petersburg, for the
same to a full and exact description hereof.

The iron frame supports a box
out of which extends above the frame a mouth piece, a upright iron is fitted in between
a cast iron front or mouth piece of any desired height, so that the top of the iron
will be between the sides of the mouth piece in such a position that the iron will
be placed being three or four inches diameter and so wide in every part that the sides
will be five or six inches broad to be from four to five feet long and just the
width of the mouth piece it secured between the two upright posts it will be
clipped on the sides of the mouth piece and held and held by the jacks so that
the ends of the sides of the box may press up against the ends of the rollers so
they rest on the mouth piece; the top and mouth piece are then secured
together with screws. A steel spring is secured on each side of the iron
with one end springing out to one of the upper rollers for causing it to roll a
little by the pressure of the iron between the rollers when necessary. The mouth
piece has a projection of four or five inches on one side, which serves as a
bearing or box for the fly wheel shaft. If the wheel is cast iron and two
and a half or three feet diameter it may be made ^{either} with iron
and which should be a regular cone from the centre of the wheel to the top
and a knife a cutter attached to each iron. The cutters are to be made such
that the height of an inch thick and curved to correspond with the curve of the
fly wheel to which they are attached. The method of attaching them is as
follows from each knife to the side of a piece of iron which fits on the curve

will of the wall and which pin is given is attached to an arm with two double
balls, the balls in the frame of iron through which the arm is to be held being longer
and may turn the other of the pin of iron so that the said pin or iron on the iron
of the wheel is now held to brass or Cattas which are attached to the wheel,
the arm being set just up to the work piece against which they both rest
by the motion of the fly wheel cut through the iron as it is brought forward
by the motion of the motor. The left σ -axis is now used to which the fly
wheel is hung, is made of iron; it is eighteen or twenty inches long and turns
parallel with the side of the fly and the work from it. Then the machine is
single geared & constructed so as to cut out the length of the iron that is com-
pared with the wheel itself over its bearing to the projection of the work
piece which rests in the top of the fly wheel but is fixed on the end of the
axis of the lead feed roller. And this roller is turned by the gearings of the
bottom end face where it puts the upper roller in motion by means of an
Achel on the other end of this roller. But then it is double geared, or, it can
be turned as to cut two or more different lengths, then to the upper end of the
fly wheel shaft is fixed a hub and wheel four and a half & five inches diameter
with sections of similar size ground into it the said σ -axis which passes down
to the bottom of the box to the other side where a piece of cast iron is turned
on it. Hence it, the end of which is a wheel on which the cutting blades are fixed
back in an iron frame so as to have an effect so that one end can be turned
to the side of the fly and the other end to the outside of the frame. On the in-
side of the frame under the outside of the box just to the left of the fly wheel
is another straight iron bar with a short iron stand σ -axis riveted into it
on which end is hung a fly wheel, eight or nine inches diameter having
a double set of pins on its face or outside and also a small pin riveted
to it on the other side which pin has gear into another nearly double as large
that is fixed on the axis of the lead feed roller. A small pinion is fixed on
the shaft of the fly wheel and is geared into one end of the fly wheel
so that by turning the pinion to work in the other way a different length of
iron will be cut. The fly wheel being put in motion either by the handle
which is bound to one of its ends or by the crank that is fixed on the end of
the metal wheel which goes round under the box.

191.

What I claim as my invention and improvement and not previously known is the above described machine & first, the method of affixing the bearings for the feeding rollers by capping the sides of the box in the sides of the front & rear. The ends of the rollers resting on the front piece and working against the ends of the side boards, as described further. Secondly the method of fixing the rollers to the ends of the fly wheel by drawing them to pieces of iron and then drawing the pieces of iron to the ends of the wheel by drawing it in a furnace and will permit them to be removable upon the ends for when attached in this way the bearing may be made very thin and is sufficiently strong and firm for the support of the pieces of iron in their holes; and they can also be accurately adjusted & cut close to the cast iron front piece without their slipping.

and Drawing is Entitled, with it
